TAP FOR BARRELS

Filed June 29, 1934

UNITED STATES PATENT OFFICE

2,043,491

TAP FOR BARRELS

Frank E. Rice, Detroit, Mich., assignor to American Tap Bush Company, Detroit, Mich., a corporation of Michigan

Application June 29, 1934, Serial No. 732,967

10 Claims. (Cl. 285—40)

The present invention relates to taps for barrels and more particularly to taps applicable to beer barrels and the like, for securing pump rods in the barrels whereby to withdraw the beer or 5 other barreled contents.

An object of the present invention is to provide a tap for barrels so constructed as to be economically manufactured for sale at reasonable prices.

10 Another object of the invention is to provide a tap of the "Peerless" type which may be cheaply manufactured for sale at competitive prices, and which at the same time possesses all of the advantages and efficiency of the "Peerless" 15 type of tap.

A still further object of the invention is to provide a beer barrel tap which is foreshortened, and which at the same time functions in all respects for efficiently seating a pump rod in a 20 barrel against dislodgment of the rod and leakage of fluid from the barrel. The tap is so constructed as to project but a short distance above the top of a barrel or keg.

A still further object of the present invention 25 is to provide a tap so constructed as to be economically manufactured with minimum labor expenditure.

Generally speaking, the invention contemplates a tap having a foreshortened body member 30 and a separate ferrule or chamber member, enveloped by the body member, and with which ferrule is an air nipple connection. The invention further contemplates a follower nut engageable with the outer body adapted for application 35 of pressure against the rod washer contained within the ferrule or inner chamber, for clamping a rod in position in the tap.

The above, other and further objects of the 40 invention will be apparent from the following description, accompanying drawing, and appended claims.

An embodiment of the present invention is 45 illustrated in the accompanying drawing, and the views thereof are as follows:

Figure 1 is a vertical sectional view through a tap constructed in accordance with the principles of the present invention, and showing a fragmental portion of a rod as clamped in the 50 tap.

Figure 2 is a vertical sectional view through the outer or enveloping member of the tap of the present invention and showing the inner or enveloped member inverted as to position, for application to or removal from the outer member.

Figure 3 is a top plan view of the tap of Figure 1, showing the inserted rod in section.

Figure 4 is a view similar to that of Figure 2, taken substantially at 90° with respect to Figure 2.

Figure 5 is a horizontal sectional view taken substantially in the plane indicated by the line V—V of Figure 1.

The drawing will now be explained.

A keg, or barrel, 1, has inserted in it a tap bush 10 2 of the "Peerless" type.

The tap of the present invention comprises two separate members, herein designated as A and B, the member A being the outer or enveloping member and the other member B being the inner 15 or enveloped member.

The outer member or body A is provided with lugs 3 which project underneath the flanges 4 of the bush 2, as is common practice.

The body A is provided with an upstanding 20 neck 5 at its upper end, which neck is interiorly threaded at 6. The wall of the body A is formed with an elongated opening or aperture 7, the purpose of which will be later explained.

The inner or enveloped member B has an interior bore in it terminating in an inwardly extending annular shoulder or ledge 8, serving as a seat for a pump rod washer 9. The surface of the shoulder 8 is inclined downwardly, as viewed in the drawing, that is toward the lower end of 30 the inner member B. The member B has its lower end undercut as at 10, with a centrally disposed flange 11, to receive a sealing washer 12. The undercut portion 10 is so shaped as to crown the sealing washer 12 as the same is tightened 35 against the flange 4 of the bush 2. The inner member B has, as an integral part thereof, a nipple 13 in the outer end of which is inserted an air valve, represented at 14, and which nipple 40 communicates through the duct 15, with the rod receiving space in the member B, for the purpose of applying air or carbonic acid gas to the interior of the barrel or keg to which the tap of the present invention may be applied.

The nipple 13 of the member B projects through 45 the aperture 7 in the member A. The inner member B is shown in operative relation, in Figure 1 of the drawing. To remove the inner member B from the body A, all that is necessary to be done is to remove the sealing washer 12 and 50 the rod washer 9, after of course the follower has been removed, as well as the rod, and with the nipple 13 as a handle, invert the member B, within the member A, as illustrated in Figures 2 and 4, whereupon the member may be readily 55

withdrawn through the bottom opening of the member A. The member B is inserted in the member A in the reverse direction, until the parts are in the arrangement of Figure 2, whereupon the member B is turned to the upright position, as illustrated in Figure 1.

For cooperating with the member B, to clamp a pump rod D in the top, a follower 16, is provided, for entering the upper end of the member 10 B, and thus centering it and also for compressing the rod washer 9. The follower 16 is herein illustrated as being connected to a nut 17 threaded to engage the thread 6 of the neck 5 of the member A, and which nut is provided with wings 18 15 for ease in manipulation. The follower is swivelled in the nut so that as the nut is turned in a direction to force the follower 16 against the rod washer 9 to compress it, the nut may rotate with respect to the follower, with the follower at rest 20 against rotative movement, thus preventing damage to the rod washer 9 by reason of the rotation of the nut 17.

When the tap is separated from a bush, the rod B is not in it, in which event the member B is 25 loose within the member A but may be retained by rattling therein by movement of the nut 17 to tighten the follower 16 against the rod washer 9.

When the tap of the present invention is applied to a tap bush, the nut 17 is loosened to permit ready application of the lugs 3 of the body A to the flanges 4 of the bush, which tap is then rotated in the usual manner until the lugs 3 strike the stops underneath the flanges 4 of the bush, which stops are not shown. The body A is provided with lugs 19 which may be used for applying the tap to or removing it from the bush. After the tap has been applied as just described, the pump rod or beer rod C is then inserted in the usual manner, and the nut 17 moved to cause the follower 16 to compress the rod washer 9 about the rod and thus secure the rod in a barrel or keg. The tightening of the nut against the rod washer 9 tends to move the inner part B toward the tap bush 2, with the result, that the body A of 40 the tap is raised, and the tap as a whole securely locked to the bush. The movement of the member B, crowns the sealing washer 12, as may be observed in Figure 1, to thus effectively seal the connection between the tap and the barrel and 45 make a leak-tight connection at the joint. The opposite faces of the rod washer 9 are parallel, and because of the inclination of the face of the shoulder 8 of the member B, and because of the fact that the opening through the lower part of 50 the member B, is slightly greater than the diameter of the rod D, gas within the barrel will bear against the under side of the washer 9 and increase the holding effect thereof against the rod C.

60 After the rod C has been secured in the manner stated, suitable connection is made to the nipple 13, with a source of air pressure, such as compressed air or a hand pump or the like, or with carbonic acid gas tank, for the purpose of creating pressure within the barrel for discharging the contents thereof through the rod C.

The tap of the present invention, effectively seals the connection between the tap and the bush and at the same time effectively retains the pump 70 rod C in position in the tap, against accidental dislodgment because of presence of gas pressure within the barrel or keg.

The tap of the present invention is economical to manufacture, in fact cheaper to manufacture 75 than the type of tap which has a nipple and bar-

rel integrally cast or united. Constructing the inner member B, in the manner herein described and illustrated, is unique, and is cheap to construct and at the same time efficient for the purpose intended.

5 The tap of the present invention may be substituted for taps of other designs that are now on the market, with full assurance that the present tap will be as efficient for the purpose intended as those now in use at the present time.

10 The invention has been described herein more or less precisely as to details, yet it is to be understood that the invention is not to be limited thereby, as changes may be made in the arrangement and proportion of parts, and equivalents may be 15 substituted, without departing from the spirit and scope of the invention.

15 The invention is claimed as follows:

1. A beer barrel tap comprising a two part structure, one part adapted to receive and envelop the other part, said other part being provided with means forming a seat for a rod washer and for receiving a rod washer, a rod washer within said other part, said one part adapted for connection to a tap bush, and a nut inserted 20 in engagement with said one part and having a follower adapted to enter said other part to center it and to engage and compress the rod washer about a pump rod inserted in said tap.

2. A beer barrel tap comprising a two part 25 structure, one part adapted to receive and envelop the other part, said other part being provided with means forming a seat for a rod washer and for receiving a rod washer, said one part adapted for connection to a tap bush, and a nut inserted 30 in engagement with said one part and having a follower adapted to enter said other part to center it and to engage and compress the rod washer about a pump rod inserted in said tap, said other part being provided with means affording connection for an air pump or the like.

3. A beer barrel tap comprising a two part structure, one part adapted to receive and envelop the other part, said other part being provided with means forming a seat for a rod washer 45 and for receiving a rod washer, said one part adapted for connection to a tap bush, a nut inserted in engagement with said one part and having a follower adapted to enter said other part to center it and to engage and compress the rod 50 washer about a pump rod inserted in said tap, said other part being provided with means affording connection for an air pump or the like, said means including a nipple obliquely disposed with respect to the axis of said other part and having a valve in its outer end, and said one part having an opening through which said nipple projects 55 when said two parts are assembled.

4. A beer barrel tap comprising a two part structure, one part adapted to receive and envelop the other part, said other part being provided with means forming a seat for a rod washer and for receiving a rod washer, said one part adapted for connection to a tap bush, and a nut inserted in engagement with said one part and 60 having a follower adapted to enter said other part to center it and to engage and compress the rod washer about a pump rod inserted in said tap, said other part being provided with means supporting a washer for sealing connection between 65 said tap and a bush, the movement of said nut to compress the rod washer causing endwise movement of said other part toward said bush for compressing said sealing washer against the bush.

5. A tap comprising a cylindrical body member having means at the lower end thereof for engaging a tap bush and having means at the upper end to receive a nut, said body having a side opening, a separate ferrule member within said body having an integral air valve stem projecting through said side opening to be available for use, said ferrule member having an inwardly directed annularly projecting flange forming a rod washer 5 shoulder, a rod washer within said ferrule on said shoulder, and a nut engageable with the upper end of said body and carrying a follower enterable into said ferrule to compress said washer about an inserted rod.

10 6. A tap comprising two separate members, one of said members adapted to receive and envelop the other of said members, said one member having at one end means for engaging a tap bush and at the other end means for receiving a washer 10 compression nut, the other of said members adapted to receive a pump rod and providing a chamber for a rod washer, said other member having in its interior an inwardly extending flange constituting a seat for the rod washer, a rod washer within said other member against said seat, a nut engageable with the said other end of said one member, and a follower on said nut enterable into said other member to compress said rod washer.

15 7. In a tap, an outer enveloping member adapted for attachment to a tap bush, an inner enveloped member adapted to receive a rod washer and provided with an annular seat for a rod washer, a rod washer within said inner member, said seat and washer surrounding an inserted pump rod, means enterable into said hollow member for centering said inner member and for compressing said washer against the rod to retain the rod in said tap, said last means being supported by and operatively associated with said outer member.

20 8. In a beer barrel tap, an outer enveloping member adapted for attachment to a tap bush, an inner enveloped member adapted to receive a rod washer within its ends and provided with an

annular seat for a rod washer, a rod washer within said inner member, said seat and washer surrounding an inserted pump rod, and means enterable into said inner member for centering said inner member and for compressing said washer 5 against the rod to retain the rod in said tap, said last mentioned means being supported by and operatively associated with said outer member.

9. A beer barrel tap comprising a two part structure, one part adapted to receive and envelope the other part, said other part provided with means forming a seat for a rod washer and for receiving a rod washer, a rod washer within said other part, said one part being adapted for connection to a tap bush, and a member having 10 threaded engagement with said one part and having a portion adapted to enter said other part to center it and to engage and compress the rod washer about a pump rod inserted in said tap.

25 10. A barrel tap including an outer hollow 20 member having means at one end for interlocking engagement with a tap bush, an inner hollow member having an annular extension for supplying pressure to the interior of a barrel, said outer member having an opening for said extension, 25 said inner member having an axial length less than the diameter of said outer member, the construction of said inner member and its extension being such that said inner member is enterable in said outer member by inserting said extension 30 in said opening and with said inner member inverted in axial direction and then rotated to erect position within said outer member, said inner member being removable from said outer member through said one end by inverting said inner member and swinging it through an arc substantially parallel to the axis of the outer member, said inner member passing said one end of said outer member with its axis substantially transversely of the axis of said outer member, and means for 35 causing relative movement of said two members in opposite axial directions for securing said tap to a tap bush and for centering said inner member with respect to the first member.
